STORAGE CONTAINER FOR FLUIDS

Wilbur G. Laird, Pleasantville, N. Y.

Application December 17, 1941, Serial No. 423,259

5 Claims. (Cl. 220—26)

This invention relates to improvements in apparatus for storing or holding fluids, and more particularly to improvements in means for restraining the tilting and tipping of the movable covers of liquid storage tanks, gas holders and storage apparatus for other fluids.

Various types of vertically movable covers have been provided for liquid storage tanks and gas holders, and various means have been provided for restraining such covers from tilting or tipping. In the storage of liquids such as petroleum oils in large upright cylindrical tanks the movable cover sometimes referred to as a floating deck or roof, a pontoon roof, or a pan, has often been sunk in the liquid or rendered inoperable because of the lack of suitable guiding means adapted to prevent tipping and tilting. Sometimes a cover, floating directly on the liquid in the tank, will be tilted sufficiently by the uneven accumulation of snow, ice or dust on one side, to sink the cover in the tank. Pontoons have been provided for such covers to prevent substantial tilting and consequent sinking, and other means have been proposed to accomplish the same result.

Gas-holder covers (sometimes called bells, lifts, piston, etc.), are sometimes provided with means for restraining any appreciable tilting or tipping. Liquid-sealed bell-type gas holders are usually provided with elevated outside frames to guide their covers, as well as any intermediate lifts. Liquid storage tanks are sometimes provided with liquid-sealed covers for holding gas or vapor above the liquid, and some means, such as guide frames, have been found necessary to keep the cover from tilting and binding. The vertically movable covers in dry gas holders are always provided with some restraining means to keep them level or to prevent tilting. Such covers are usually provided on top with extensive framework, with rollers which operate on the inside wall of the holder at a considerable distance above the cover proper. Proposals have been made for the use of sets of cables for preventing such movable covers from tilting.

Some covers used in oil storage tanks are supported at all points on the liquid oil and are used to retard evaporation and not intended to prevent escape of all vapors. The rigid portions of these covers are often considerably smaller than the normal internal tank diameter, because such tanks are neither accurate nor smooth, and are merely provided with a loose marginal seal which engages the wall of the tank. In the case of dry gas holders however the shell is built ac-

curately to size and the movable cover is provided with a marginal gasket-type seal which is substantially gas-tight. Covers which are sealed in liquid, either for liquid storage containers, for gas and liquid containers, or for gas holders or containers, are of course gas- or vapor-tight inside the seal under normal conditions of use.

Since all of these and similar movable covers for storage containers for fluids must be kept from tilting and tipping, the primary object of the present invention is to provide a new and effective means or mechanism for preventing the tilting, binding, tipping and upsetting of movable covers for storage containers for fluids.

Another object of the invention is to provide a new and effective means or mechanism for restraining the tilting of the movable cover of a fluid storage container of the type in which the cover moves up or down in response to the increase or decrease of the volume of the fluid in the container.

A further object of the invention is to reduce the cost of constructing storage containers for fluids in which the containers are provided with covers which move in response to changes in the volume of the fluid in the container.

A still further object of the invention is to provide a new and improved mechanism for keeping the movable cover of a container for fluids, in its normal position of movement with respect to the walls of the container, while at the same time allowing the cover to move up or down in response to the increase or decrease of the volume of fluid in the container.

According to the invention the apparatus for storing or holding fluids comprises an upright container, a cover for the fluid to be held therein adapted to be supported by the fluid and to be moved up or down in response to increase or decrease of the volume of the fluid in the container, and means for restraining substantial tilting of the cover during such movement, said means preferably including several (more than two) link units distributed around said container and cover, each of said units including a connecting-bar with a bearing at each end, one end of each unit being pivoted to respond to the movement of the cover and the other end being pivoted to the container or other member in a fixed horizontal plane, the corresponding connecting-bars of all units being mounted at the same angle to the horizontal and for simultaneous concordant motion with the cover, said link units being arranged to act simultaneously and positively in response to the motion of the cover, to

restrain said cover from substantial tilting under all normal conditions.

Other objects, features and advantages of the invention will be apparent to those skilled in the art from the following detailed description taken in connection with the accompanying drawing in which:

Fig. 1 is a broken elevational view of an upright cylindrical-type container in which one form of link restraining means of the present invention is illustrated.

Fig. 2 is a broken horizontal sectional view taken on the line 2—2 of Fig. 3.

Fig. 3 is a broken vertical sectional view of a container particularly adapted for holding liquids and having a floating deck-type cover, in which another form of the link mechanism is illustrated.

Fig. 4 is a broken horizontal sectional view taken on the line 4—4 of Fig. 5, showing only a part of the apparatus shown in Fig. 5.

Fig. 5 is a broken vertical sectional view of a container of the dry gas-holder type in which still another form of the link restraining mechanism is illustrated.

Fig. 6 is a broken vertical sectional view of a container similar to that illustrated in Fig. 1 taken on the line 6—6 of Fig. 7, in which a further form of the link restraining mechanism is illustrated.

Fig. 7 is a broken front elevational view of the apparatus shown in Fig. 6.

Fig. 8 is a broken horizontal sectional view taken on the line 8—8 of Fig. 7.

From a consideration of the various figures shown in the drawing it will be apparent that the improved link mechanism, for restraining the tipping of movable covers used in connection with containers for storing or holding fluids, has general application to various types of containers and covers, as will be pointed out hereinafter.

The storage container illustrated in Fig. 1 of the drawing is of the general type of cylindrical oil tank provided with a bell-type cover for holding vapors and gases, the bell being sealed in the liquid in the tank. The tank shell is shown at 10 and the bell-cover at 12. The tank shell is preferably provided with an angle-iron curb 14, an oil inlet and outlet 16 and a gas inlet and outlet 18, the latter extending to a point above the top of the tank as shown. The cover in this instance is provided with a central hood member 20 which passes over the top of the gas conduit 18 as shown in dash and dot lines in connection with the showing of the bell cover in lowered position in the container. The bell-cover is shown as being provided with the usual rollers 22 around its lower circumference for engaging the wall of the container as the cover moves up and down therein with changes in volume of fluid (liquid, gas or vapor) in the container. The means for preventing the tilting of the cover 12 in this instance consists of a number of stiff link members 24 (three or more), distributed around the periphery of the cover and container, one end of each link-member being connected to the cover through a pivot joint or bearing 26, while the other end is connected through a similar bearing 28 with the rim of the container 14, as shown. The bearing joints 26 and 28 preferably include suitable brackets which are bolted, welded or otherwise fastened to the cover or container as the case may be.

The links 24, which are preferably made of relatively strong material, are all of the same length, all placed at the same angle with respect

to a horizontal plane, and preferably all set in the same relative position with respect to the cover and container. Under these conditions any movement of the cover 12 up or down from a given position is accomplished without any tilting because the series of links distributed around the cover and container act to hold the cover to movement in the same direction, the same distance at all points. In the particular arrangement shown in Fig. 1, the single links cause the cover to rotate slightly in the container as it moves up or down, because the bearings 28 are fixed. The points corresponding to bearings 26 therefore describe a definite arc or motion as the cover 12 moves through the range of movement permitted by the particular container and cover. Landing blocks and crown supports, not shown, are usually provided within the container for the cover to rest on when the liquid therein is withdrawn completely or to a definite predetermined extent.

In the arrangement shown in Fig. 1 the movement of the cover may be through a distance which may approximate twice that of the length of the links 24, so that links of great length are not necessary. The links however may be mounted so that the points 26 are always above, or always below the level of the points 28. The series of links 24 not only keep the cover 12 from tilting but also maintain it concentric with the container, if both are circular in cross-section. Rollers 22, therefore, while of use in some cases, are not essential. If the container 10 is of small diameter compared to its height, and the links are arranged to pass between the cover and container, the links 24 may be bowed to the curvature of the container. The joints at 26 and 28 may be of the ball and socket or universal type or of any other suitable design.

The apparatus illustrated in Fig. 1 is particularly adapted for the storage of various petroleum products such as gasoline and crude oil, in which the vapors are trapped under the cover 12 and retained without loss, or discharged through the line 18. The apparatus furthermore may be advantageously used as a so-called breather-type tank to hold both oil and vapor and may receive additional gas or vapor through the line 18, or may be used exclusively as a gas holder.

The apparatus shown in Figs. 2 and 3 illustrates another form of container 30, particularly adapted for the storage of volatile liquids, which is provided with a floating cover 32 slightly smaller than the internal diameter of the container. In this instance, the cover as illustrated is of the pan-type and is provided with the usual container wall-rollers and with a flexible sealing member 34 such for example as a mat seal, which is fastened to the rim of the cover, as shown, and which bears against and is movable along the wall of the container 30 as the liquid level changes. The seal 34 is not a gas-tight seal, but merely serves to reduce evaporation losses and prevent air currents from entering the space between the cover 32 and the wall of the container. The floating cover shown in Figs. 2 and 3 is held in substantially horizontal position, or prevented from tilting because of unequal loading and other conditions met with in practice, by providing a number of radially mounted link units distributed around the periphery of the cover and container, such as the unit shown in front view in Fig. 3. This link unit consists of an upper link or connecting bar 36 having one end attached to a bracket at the top of the con-

tainer 30 through a bearing 38, and having the other end connected through an end bearing to a similar link 40, which in turn is connected through a bracketed bearing 44 to the cover 32, as shown. The link unit also includes a third link 46 of the same length as the links 36 and 40. The links 40 and 46 are connected at their midpoints by means of a bearing pin or other suitable pivot joint, while the upper end of the link 46 is pivoted to one end of a short link 48 by an end bearing joint. The short link 48 which is half the length of the links 36, 40 and 46 is connected by a pivoted end bearing to the midpoint of link 36.

The lower end of the link 46 is provided with a roller 50 which operates along a horizontal surface of the cover 32 as the cover moves up or down in the container. It will be apparent that as the position of the cover 32 changes in the container with changes in the volume of liquid therein, the link mechanism will extend or retract and roller 50 will move radially along the horizontal surface of the cover. With from three to twelve or more of the link units shown in Fig. 3 distributed around the periphery of an oil storage tank, it is possible to prevent tilting of the cover 32 by suitably interconnecting the lower ends of the links 46 of the link units, or by merely interconnecting the lower ends of the links 46 of units on opposite sides of the cover. The method of interconnecting all of the link units is illustrated in Figs. 4 and 5 and will be referred to hereinafter; while the method of connecting opposite link units is shown in Figs. 2 and 3, in which the lower portion of the link 46 of opposite units is attached to a motion conveyor such as a taut endless cable or chain 52 by means of a cable clamp 54, and suitably mounting the cable around sheaves 56 on opposite sides of the cover. The sheaves 56 are attached to the cover 32 outside of the pivots 44. It will be readily apparent that since the cable clamps 54, on the two opposite units, are on opposite sides of the endless cable loop, that the rollers 50 for both units must move together, if at all, radially toward or away from the center of the cover, so that these opposite link units must function in unison and therefore prevent any substantial tilting of the cover. The use of two or more pairs of such units, in accordance with the size of the container, will be sufficient to prevent any substantial tilting of the cover. Furthermore, for the particular container and cover, the relationship of the various links shown in Fig. 3 is such that the pivot point 44 will move vertically with respect to the point 38.

A series of link units as shown in Figs. 2 and 3 may be used on any type of movable cover, such as pontoon roofs, pistons, bells, etc. The bracket for the fixed pivot point 38, may be attached to any stationary element other than the container wall, and the units may be inverted if desired so long as provision is made to guide the roller 50 in a horizontal path.

The container illustrated in Figs. 4 and 5 is of the general type of dry gas holders and may be cylindrical or polygonal as desired. In this instance, the apparatus comprises a bottom plate 60, a side wall or shell 62 of any desired height, and a piston type cover 64 provided with a packing seal 66. Since such an apparatus is used exclusively for holding gas some means is always provided to prevent the tilting of the piston, and in the present instance the improved link unit restraining means is illustrated and used for that purpose.

In Fig. 5, two of the link units are shown, each

consisting of an upper link 68 having an end bearing attachment to a fixed bracket on the rim of the cover at 70, and an end attachment with a similar link 72. The link 72 has a bearing attachment at 74 to a bracket fixed to the bottom plate 60, and a midpoint bearing attachment with a third link 76, which in turn has its upper end pivoted to one end of a half-length link 78. The link 78 is also attached by its other end to the midpoint of the link 68 by means of a bearing pin or similar pivot member.

The lower end of link 76 is provided with a roller 80 and the link unit as a whole functions in substantially the same manner as the link unit shown in Fig. 3, except that movement of the roller 80 is restricted by means of a retaining guide member 82, fastened to the container bottom 60.

The motion conveying means for securing simultaneous action of all of the link units (preferably 3 or more) used in the container of Figs. 4 and 5, comprises an endless cable 84 extending entirely around inside the container and mounted on sheaves 86 secured to the bottom plate 60 in the arrangement shown, so that a section of the cable adjacent each link unit is substantially parallel to the plane of the unit (see Fig. 4). The cable is fastened to the lower end of each link 76 by means of a cable clamp 88 at a time when the cover 64 is substantially level and all of the link units are extended to the same degree. After the clamps 88 are secured to the cable, all of the link units must function at the same time and in the same manner, as the cover 64 moves up or down, so that the pivot points 70 must all move through the same distance at the same rate. In the particular showing in Figs. 4 and 5, the links 68, 72 and 76 are of the same length and therefore the pivot point 70 for each unit must move vertically with respect to the point 74. The guide members 82 prevent any other motion. The link units of Figs. 4 and 5 may be used on any type of cover, in the stored fluid or outside.

The storage container shown in Figs. 6, 7 and 8 is similar to that shown in Fig. 1 and comprises a shell 90 and a deep bell-type cover 92 sealed in liquid in the container and normally containing vapor or gas above the liquid. The link units illustrated in these figures each include a long link 94 pivoted by its upper end at 96 to a bracket on the cover as shown, and by its lower end at 98 to a bracket fixed to the inside of an endless movable channel-iron track or band 100. A short or half-length link 102 is pivoted by its upper end to the midpoint of the link 94 and by its lower end at 103 to a bracket member 104 which is fixed to the upper part of the container shell 90. The endless channel band 100 extends entirely around the container and is held in substantially the horizontal position shown by means of a plurality of rollers 106 mounted on the brackets 104 (other brackets may be used), the rollers extending into the channel member. Since there will be from three to twelve or more brackets 104, and a suitable number of rollers 106, the endless channel band will be free to move on these rollers. All of the links 94 and 102 will be set at the same angle to the horizontal and preferably in the same position with respect to the cover and container shell, so that the endless channel band 100 will serve to connect all of the link units, and when cover 92 moves it will cause all of the bearings 98 to move at the same time and rate, and for the same distance. For example, if the volume

of vapor is decreased under the cover 92, the cover will settle into the liquid in the shell 90 and all points 96 will be moved vertically down toward the respective lower pivot points 103 of the links 102. At the same time the channel member 100 will be moved to the right in Figs. 7 and 8, so that all points 98 will move to the right to the same extent, regardless of the fact that the cover might apply greater stress on one unit than on another. In fact the cover may be forcing one point 96 down while on the opposite side of the container at another point 96, the link unit there may be pulling the cover down, because of the band 100 connecting all of the units.

The cover 92 in Figs. 6, 7 and 8 does not rotate in the container because of the link 102 and its direct connection at 103. The link 102 however is not essential to prevent tilting of the cover, because the band 100 is always horizontal, and the series of links 94, in the absence of links 102, would function the same as the links 24 in Fig. 1. Instead of using the band 100, the movement of the pivots 98 can be suitably restricted by the use of guides, such as 82 shown in Fig. 5, attached to the rim of the shell 94, if the pivots 98 are provided with rollers such as the roller 80. The pivot point 98 must be restricted to a horizontal motion in order to produce a vertical motion for the pivot point 96.

Tracks or bands of the type of the band 100 shown in Figs. 6, 7 and 8 may be used in other positions to interconnect link units. For example, the apparatus shown in these figures might be provided with an upper horizontal band mounted on rollers like 106, but which are attached to the upper rim of the cover 92, the upper ends of links 94 then being pivoted to the upper band like they are at 98 to the band 100. One or two such bands or their equivalent may be used in connection with the links of Figs. 1, 4 and 5. Where one or two such bands or tracks are used with the links of Fig. 1, the cover may be guided in a vertical path if desired. In the case of two movable tracks, each link 24 would be pivoted to each track, and therefore, while the links 24 would be connected with the container or the cover, they would not be directly connected.

A series of link units such as used in Fig. 1 may be used for covers of the type shown in Fig. 3, or on the usual pontoon cover or roof. It may be preferable in such cases however to avoid rotation of the cover, as for example by using one or two movable horizontal tracks as explained above.

The link units may be effectively used on liquid-sealed, so-called expansion roofs, or covers, with the link units either inside or outside the cover and container, thus avoiding the use of expensive frames or other expensive arrangements for counterbalancing and stabilizing such covers. Furthermore the link units may be applied to the different lifts of a multiple lift container or gas holder, such as the well-known liquid-sealed gas holder, and thereby eliminate all of the extensive outside framework commonly employed to guide the succession of lifts. All that is necessary is to provide several link units, such as those illustrated in Figs. 1, 5 and 7, between the upper rims of adjacent lifts and between the upper rim of the lowermost lift and the stationary part of the holder or some fixed suitable structure.

Instead of connecting the links with a fixed part of the container as at 28 in Fig. 1, 38 in Fig.

3, 74 in Fig. 5, and 103 in Fig. 6, they may be mounted in pivoted relation to any fixed object such as a column, pier, abutment, or frame; or to a stable pontoon ring, or ring of pontoons, floating on liquid inside the container under, inside or below the cover. Likewise, instead of using cables or chains as described in connection with Figs. 2, 3, 4 and 5, suitable leverage mechanism or rack and pinion arrangements or other desired motion conveying elements may be used for simultaneously operating the link units of a given set in response to any movement of the cover. The attachments of the link units to the cover or to the relatively stationary part of the apparatus need not be direct, and need not be by a close connecting member. Guided extension rods or bars may be used. While at least three link units are necessary in order to completely stabilize a cover or prevent its tilting where such units are used alone, it is to be understood that two or even one link unit may be employed along with other means for preventing the tilting of the container cover. For example, one or more link units may be used along with one or more sets of cables used in the manner described in the applicant's Patents Nos. 1,894,535-6-7 and 2,050,707. Two interconnected link units mounted on opposite sides of a cover from each other may be used along with a cable or pair of cables mounted at right angles to a line through the two link units. Individual links or a plurality of links may also be employed along with restraining means other than the cables referred to. Covers of the type shown in Figs. 1, 6, 7, and 8 may be so heavy as to throw too high a gas pressure, and therefore need counterweighting. This can be accomplished simply in Fig. 1, for example, by using double length links with the pivots 28 mounted outside the shell 10 and at about the midpoint of the links, with the lower portions left to swing free. Now if weights are attached to the free ends of the links they become levers for counterweighting the cover.

Counterweights may be applied to the cover by using levers separate from the links or by any usual mechanism.

The link units shown in Figs. 3 to 8 may include any suitable number of pairs of long links. For example, additional links like the pair 40 and 46 in Fig. 3, may be hinged to the lower ends of these links and to each other in the same manner that the pair of links 40 and 46 are hinged together and to the lower ends of links 36 and 48.

It is to be understood that the phrase "link unit" as used in the appended claims is intended to include any link mechanism adapted to transmit stress or motion to or from the part of the movable cover with which it is associated, and that the link units may be connected directly or indirectly with the cover and container (or a relatively fixed object) so long as they are influenced positively by the movement of the cover.

Having described the invention and illustrated the same in connection with certain specific examples, what is claimed as new is:

1. An apparatus for holding fluids, comprising an upright container provided with a movable cover normally adapted to be moved up or down respectively with corresponding changes in the volume of fluid held in the container, and means for preventing the tilting of the cover during its normal movement in response to changes in the volume of fluid in the container comprising a

series of at least three similar link units spaced with respect to each other and substantially evenly distributed around the container and the outer portion of the cover in the same relation thereto, each of said units including a plurality of links interconnected to form a vertically extensible and retractable mechanism, one end of each unit being connected to the cover by a pivot joint at the end of a link, the other end of the unit being connected to a fixed part of the apparatus by a pivot joint at the end of a different link, means interconnecting said units for simultaneous movement in the same direction including means connected to the end of a link at the same end of each unit, and means for restricting the movement of said last mentioned link end of each unit to a predetermined plane.

2. In an upright cylindrical type container having a cover movable up and down with the increase and decrease in the volume of fluid held therein, link means for restraining substantial tilting of the cover comprising several interconnected spaced link units substantially evenly distributed around the outer portion of said container and cover, each of said units including a stiff link with a bearing at each end, one of which is attached to the cover and the other end of which is attached to a means for interconnecting said units, each unit including a short link about half the length of said stiff link having one end pivoted to the midpoint of said stiff link and the other end pivoted to the container, said links being mounted in the same angular relation to said container in one direction therearound, and means for confining said interconnecting means to movement in a predetermined substantially horizontal plane.

3. In an upright cylindrical type container having a cover movable up and down with the increase and decrease in the volume of fluid held therein, link means for restraining substantial tilting of the cover comprising several interconnected spaced link units substantially evenly distributed around the outer portion of said container and cover, each of said units including a stiff link with a bearing at each end, one bearing of all links being connected to the cover at the same level and the other end of each link being attached to a movable means for interconnecting said units, each unit including a short link about half the length of said stiff link having one end pivoted to the midpoint of the stiff link thereof and the other end pivoted to the

5 container, the respective links of each unit being mounted in the same angular relation to said container in one direction therearound, and means for confining said interconnecting means to movement in a predetermined substantially horizontal plane.

10 4. In an upright cylindrical type container having a cover movable up and down with the increase and decrease in the volume of fluid held therein, link means for restraining substantial tilting of the cover comprising several interconnected spaced link units substantially evenly distributed around the outer portion of said container and cover, each of said units including a stiff link with a bearing at each end, one bearing of each link being attached to the cover and the other bearing of which is attached to a movable circular band for interconnecting said units, each unit including a short link about half the length of said stiff link having one end pivoted to the midpoint of said stiff link and the other end pivoted to the container, the respective links being mounted in the same angular relation to said container in one direction therearound, and means for confining said circular band to movement in a predetermined substantially horizontal plane.

15 5. An apparatus for holding fluids, comprising an upright container provided with a movable cover normally adapted to be moved up or down respectively with corresponding changes in the volume of fluid held in the container, and means for preventing the tilting of the cover during its normal movement in response to changes in the volume of fluid in the container comprising a series of at least three similar link units spaced with respect to each other and substantially evenly distributed around the container and the outer portion of the cover in the same relation thereto, each of said units including a plurality of links interconnected to form a vertically extensible and retractable mechanism, one end of each unit being connected to the cover by a pivot joint at the end of a link, the other end of the unit being connected to a fixed part of the apparatus by a pivot joint at the end of a different link, and movable means interconnecting said units for simultaneous concordant movement, said means being connected to the end of a link of each unit.
